John Martino
John Currie

John Martino, and John Currie, of Philadelphia, Penn^s.
assign to

Stuart and Peterson, of the same place.

Letters Patent No. 2094 - Dated June 18 - 1865.

Ante-dated May 30 - 1865.

Design for a Portable Range.

The schedule referred to in these letters Patent and making part of the same.

To all whom it may concern:

Be it known that we, J. Martino, and J. Currie, both of Philadelphia, County of Philadelphia, State of Pennsylvania, have invented or produced a new and original design for a Portable Range, termed the "Fulton"; and we do hereby declare the accompanying drawing, with the following explanation of the same, to form a full, clear and exact description of the said design.

In the drawing A is the side plate of the Fulton cook range, at each edge of which is a plain beading a; and at the lower edge is a more ornamental beading b.

To the plate is hinged a door A, which is edged with a beading c, and in the centre of the plate is an ornament B, which is surrounded by an oval beading f.

On the plate at one side of a door A is a panel C, which is edged with a beading similar to the beading c, and in the centre of the panel is an ornamental oval beading e.

To the feed opening above the panel C is adapted a plate D, which is edged with a plain beading i, and an ornamental beading j; and in the centre of the plate is the word "Fulton".

The draught register below the panel C is edged with a plain beading m, and near the latter are four ornamental figures o, corresponding to similar figures on the door A.

DES. 2094

2

McClure

The ornamental figures and forms, substantially as shown and by the accompanying drawing, the whole forming an ornamental design for the side plate of the Fulton, portable range

In testimony whereof we have signed our names to this specification in the presence of two subscribing witnesses:

Henry Cowdon (Witness)

John Martin

J. J. W. J. R. Massey (Witness)
